(57) **CLAIM**

The ornamental design for a vehicle dashboard display screen with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a vehicle dashboard display screen with graphical user interface, showing an embodiment of our new design with surrounding environment.

FIG. 2 is a front view of the vehicle dashboard display screen with graphical user interface of FIG. 1 without the surrounding environment.

FIG. 3 is a front view of a vehicle dashboard display screen with graphical user interface, showing another embodiment of our new design with surrounding environment.

FIG. 4 is a front view of the vehicle dashboard display screen with graphical user interface of FIG. 3 without the surrounding environment; and,

FIGS. 5 through 56 each show a front view of a vehicle dashboard display screen with graphical user interface, showing additional embodiments of our new design.

The outer dash-dotted lines in the drawings depict the outer perimeter of the vehicle dashboard display screen for environmental purposes and form no part of the claimed design. The broken lines in the drawings depict the boundaries of the claimed design. The washed-out images in FIGS. 1 and 3 between the outer dash-dotted lines and the broken lines of the claimed design show surrounding environment and form no part of the claimed design.

1 Claim, 56 Drawing Sheets
